UNITED STATES PATENT OFFICE.

ARTHUR H. WHITE, JOHNSTON C. HUSTON, AND GEORGE H. DICKEY, OF BRACKENRIDGE, PENNSYLVANIA.

MACHINE FOR CLEANING AND POLISHING ROLLS FOR ROLLING-MILLS.

1,174,213.

Specification of Letters Patent.

Patented Mar. 7, 1916.

Application filed May 26, 1915. Serial No. 30,570.

To all whom it may concern:

Be it known that we, ARTHUR H. WHITE, JOHNSTON C. HUSTON, and GEORGE H. DICKEY, citizens of the United States, residing at Brackenridge, in the county of Allegheny and State of Pennsylvania, have invented certain new and useful Improvements in Machines for Cleaning and Polishing Rolls for Rolling-Mills, of which the following is a specification.

This invention relates to a machine for cleaning and polishing rolls of rolling mills, plate glass, hard-wood floors, or anything requiring a smooth or oil finish surface, and has for its object to provide a portable cleaning machine.

Another object of the invention is to provide a roll cleaning device having means for cleaning a plurality of mill rolls at one time.

Another object of the invention is to provide a portable roll cleaning device having a stationary motor for operating the same.

Still another object of the invention is to provide a portable roll cleaner having a carriage upon which it travels.

A further object of the invention is to provide a portable roll cleaner moving means whereby its position relative to the rolls being cleaned may be quickly adjusted.

With the above and other objects in view which will be more fully described hereinafter, we have invented the device illustrated in the accompanying drawings in which—

Figure 1 is a sectional elevational view of our machine shown in operative position, Fig. 2 is an end elevation view thereof shown, Fig. 3 is a top plan view thereof, Fig. 4 is a fragmental side elevation of a casing and, Fig. 5 is an enlarged detail sectional view of a cleaning and polishing wheel.

Like reference characters indicate like parts throughout the specification and in the several views in the drawings in which 6 indicates a casing having a web 7 upon which is formed a bearing 8 for one end of the shaft 9, the other end of which is mounted in the bearing 10 formed on said casing. Said shaft 9 carries a bevel gear 11 which operates the bevel gear 12 on the shaft 13. A gear 14 is carried by the gear 12 which operates the gear wheel 15 which in turn directly operates the pinion 16 fixed on the

shaft 17 and indirectly rotates the pinion 18 fixed on the shaft 19 through the transmission gear 20.

On each end of the shafts 17 and 18 are polishing rolls 21 and 22 which are formed by a plurality of fabric disks 23 tightly clamped between the frusto-conical members 24 and 25 which are tightened upon said disks by means of the units 26 screw threaded upon the ends of said last named shafts. 60 The flexibility of said rolls 21 and 22 may be regulated by tightening or loosening said units 26. Collars 27 are fixed upon shafts 17 and 18 against which the members 24 abut.

A carriage 28 has one end pivotally mounted at 29 to said casing 6 and its other end carries a rod 30 with cams 31 operating in pockets 33, which, by means of the operation of the crank 34 fixed to the rod 30, will cause them to engage the under wall 35 of the casing 6, and thereby change the relative position of said casing to the rolls 36 and 37 which are being cleaned and polished. The carriage is provided with rollers 38 and 39 80 which are adapted to rest upon any suitable beam or part of a mill frame (not shown) most suitable upon which to seat the machine. The casing 6 is provided with suitable handles 40 and 41 by means of which 85 the device may be readily manipulated.

A flexible device shaft 42 connects the shaft 9 to the motor 43 by means of which the machine is driven.

The casing 6 is provided at one end with 90 recesses 44 and 45 in which the cleaning rolls 21 and 22 seat. The carriage 28 is provided with standards 46 and 47 between which said casing seats.

The rolls 21 and 22 may be made to have 95 relatively hard peripheral surfaces by tightening the units 26 thereby very tightly binding said disks 23 together; in that condition the rolls will clean scale or other adhering matter from the rolls 36 and 37 and 100 by loosening the units 26 the disk surfaces will become more pliable and will act as polishers. The disks 23 are of a greater diameter than their binding members 24 and 25 whereby the disk edges will overlie the 105 edges of said binding members thus guarding against said binding members coming into contact with the rolls being cleaned and polished. The shape of said members 24 and 25 also act to stiffen them and make 110

them more tightly bind the disks together than if they were flat disks.

Having now described our invention that which we claim to be new and desire to procure by Letters Patent is:—

- 5 1. The described device consisting of a casing, rollers whereby said casing travels and polishing rolls mounted in vertical alinement with one another.
  - 10 2. The described device consisting of a casing, rollers whereby said casing travels and polishing rolls mounted in vertical alinement with one another and projecting from one end of said casing.
  - 15 3. The described device consisting of a casing, rollers whereby said casing travels and polishing rolls mounted in vertical alinement with one another and projecting from one end of said casing, and one of 70 20 said rolls projecting above the upper wall of said casing.
  - 25 4. The described device consisting of a casing, rollers whereby said casing travels and polishing rolls mounted in vertical alinement with one another and projecting from one end of said casing, one of said rolls projecting above the upper wall of said casing, and another of said rolls projecting below the bottom wall of said casing.
  - 30 5. The described device consisting of a casing, rollers whereby said casing travels and polishing rolls mounted in vertical alinement with one another and projecting from one end of said casing, and an adjustable bearing for said rollers.
  - 35 6. The described device consisting of a casing, rollers whereby said casing travels and polishing rolls mounted in vertical alinement with one another and projecting from one end of said casing, an adjustable bearing for said rollers, whereby they may be angularly adjusted, means for adjusting said bearings, and said means consisting of a cam member.
  - 40 7. The described device consisting of a casing, rollers whereby said casing travels and polishing rolls mounted in vertical alinement with one another and projecting from one end of said casing, an adjustable bearing for said rollers, whereby they may be angularly adjusted, and said rolls projecting beyond one end of said casing.
  - 45 8. The described device consisting of a casing having top, bottom and end walls, a carriage whereby said casing is mounted and polishing rolls projecting beyond one of said end walls.
  - 50 9. The described device consisting of a casing having top, bottom and end walls, a carriage whereby said casing is mounted and 60 65 polishing rolls projecting beyond one of said end walls, and means for operating said rolls, to rotate in opposite directions.
  - 55 10. The described device consisting of a casing having top, bottom and end walls, a carriage whereby said casing is mounted and 70 75 polishing rolls projecting beyond one of said end walls, means for operating said rolls to rotate in opposite directions, said carriage being pivotally mounted on said casing.
  - 60 11. The described device consisting of a casing having top, bottom and end walls, a carriage upon which said casing is mounted and polishing rolls projecting beyond one 80 85 of said end walls, means for operating said rolls to rotate in opposite directions, said carriage being pivotally mounted on said casing, and means for adjusting the position of said carriage relative to said casing.
  - 65 12. The described device consisting of a casing, rollers mounted longitudinally thereof whereby the casing may travel transversely of its length.
  - 70 13. The described device consisting of a 85 casing, rollers mounted longitudinally thereof whereby the casing may travel transversely of its length, and polishing rolls mounted on said casing and rotatable in a direction opposite to the line of travel of 90 95 said carriage.
  - 75 14. The described device consisting of a casing, rollers mounted longitudinally thereof whereby the casing may travel transversely of its length, polishing rolls mounted on said casing and rotatable in a direction opposite to the line of travel of said carriage, and means for rotating said rolls in opposite directions.
- In testimony whereof we affix or signa- 100 tures in presence of two witnesses.
